UNITED STATES PATENT OFFICE.

JOHN FREDRICK BENDER, OF HAMILTON, OHIO.

FREEZING-TANK.

1,114,957.

Specification of Letters Patent.

Patented Oct. 27, 1914.

Application filed August 15, 1913. Serial No. 784,856.

To all whom it may concern:

Be it known that I, JOHN FREDRICK BENDER, a citizen of the United States, residing at Hamilton, Butler county, Ohio, have invented certain new and useful Improvements in Freezing-Tanks, of which the following is a specification.

This invention, pertaining to improvements in the construction of freezing tanks employed in the manufacture of ice, will be readily understood from the following description taken in connection with the accompanying drawings, in which:

Figure 1 is a vertical transverse section of a freezing-tank embodying an exemplification of my invention; and Fig. 2 a plan of the same, the covers of some of the cans being removed and portions appearing in horizontal section.

In the drawings:—1, indicates the outer casing of the general tank structure; 2, its floor; 3, the tank, disposed within the casing; 4, the floor of the tank; 5, insulating filling disposed in the space between the tank and casing; 6, a superfloor for the tank; 7, supports disposed upon the floor of the tank and serving to support the superfloor and leave a space between the floor and superfloor of the tank; 8, the cans disposed in rows within the tank and separated from each other and from the tank-walls, the top of the cans being open and the footings of their walls having water-tight connection with the superfloor of the tank; 9, the brine-spaces surrounding the cans; 10, grid-work surrounding the tops of the cans and separating them from each other and from the tank walls, this grid-work projecting above the top of the cans and so fitting the brine-

spaces 9 as not to be airtight; 11, the removable can-covers seated on the grid-work 10; 12, the brine inlet-pipe leading into the base of brine-space 9 near one corner of the tank; 13, brine outlet-pipe leading out of brine-space 9 near a corner of the tank diagonally opposite the brine inlet-pipe; 14, framework at the top of the space between casing 1 and the wall of the tank; 15, the space between the floor and superfloor of the tank; 16, water inlet-pipe leading up into space 15 and, preferably, at center of the space; 17, a fender disposed over inlet-pipe 16; 18,

a manhole giving access to space 15; 19, a large opening through the superfloor of the tank at the base of each can; 20, a nipple disposed at each of these openings and extending downwardly into space 15; 21, an air-jet pipe extending along under each row of nipples; 22, supporting saddles for these air-jet pipes; 23, a closed air-pipe communicating with the upper portion of space 15; 24, a vent-cock connected with this air-pipe; 25, a pressure-gage connected with pipe 23; 26, a manifold connecting air-pipes 21; 27, a thaw-water inlet pipe leading into space 15, near one corner of the space; and 28, a thaw-water outlet-pipe leading from space 15 near the corner of the space diagonally opposite thaw-water inlet-pipe 27.

It will, of course, be understood that while the structure illustrated comprehends only sixteen cans, the system will lend itself to any desired number, and that all of the piping may be arranged in the manner most convenient for the situation and that the piping will be connected with suitable means for supplying the material which is to pass through the pipes, and for controlling the flow therethrough.

It will be obvious that the general structure is extremely simple and substantial in construction, and easily repaired in case of injury or decay of parts. The insulating material 5 may well be of granulated cork; the grid and cover-work may well be of wood; the outer casing of wood; and the other parts of metal. The cans, or any individual one of them, are readily removed from the tank by disconnecting the screws uniting their bases to the superfloor of the tank.

Assume the structure to be empty and out of use, and assume that the refrigerating material to be employed in space 9 is cold brine. The cold brine is to enter and fill and pass through the brine-spaces 9; the water to be frozen is to be admitted at pipe 16; this water partially fills space 15 and gradually fills the cans; the refrigeration of the water begins and continues while the cans are filling; air under pressure is admitted to pipes 21 and jets up through nipples 20 and into the water in the cans, bringing about a general circulation of the water

within the cans to facilitate the freezing action by bringing all of the water into contact with the walls of the cans, the air at the same time working impurities upwardly; the water in space 15 and in the cans will not fill the upper portion of space 15 but will be trapped under the superfloor around the nipples; this trapping of air retards the freezing at the base of the cans; 10 fender 17 over the water-inlet-pipe serves in distributing the entering water in space 15; the flow of water is to be arrested when the cans are sufficiently full; the flow of the brine is to be continued until the ice in the 15 cans is properly formed and ready for removal therefrom; the air-jets may be cut off when congelation has so far proceeded that the jets can do no further good; gage 25 may serve in indicating when the inflow 20 pressure of water at pipes 16 is just sufficient to fill the cans to the desired level, without overflowing them.

The ice having been formed in the cans, ready for removal, the inflow of cold water 23 from pipe 16 is to be cut off; thaw-water is to be admitted to space 15 through pipe 27 and depart through pipe 28, keeping space 15 filled; vent 24 is to be opened, permitting the trapped air to leave the upper portion 30 of space 15; the thaw-water thus has access to the under surface of the floor of the tank and to the nipples; the action of the thaw-water is to melt and loosen such ice as may have frozen into adhesion to the superfloor 35 and nipples; a warming agent is to be substituted for the cold brine circulating in spaces 9; this warming agent may be a warm brine or any other suitable warming liquid; the circulation of the warming agent in 40 spaces 9 breaks the adhesion of the cakes of ice to the walls of the cans; the cakes are readily lifted from the cans; lifting-eyes or other grapple-receiving devices may be frozen into the top of the cakes to facilitate 45 their removal by a crane.

A metallic superfloor is disposed between the freezing water in the cans and the water in compartments 15. If this were all then there would be a tendency toward freezing 50 in compartment 15 and a consequent clogging of the air-jets, in addition to the undesired freezing at the bases of the cakes. But in the present example the water in space 15 is kept away from the superfloor 55 by the insulating air trap below the superfloor. This insulation is removed when the thawing is to be done.

I claim:

1. A freezing-tank comprising, a can to 60 hold water to be frozen, a tank surrounding the can to hold a frigorific mixture around the can, a closed space below the floor of the can, means for confining insulating air in

said space while the water in the can is freezing, and means for venting said air and 65 supplying thaw-water to said space when the forming of the ice in the can is completed, combined substantially as set forth.

2. In freezing tanks, the combination of a refrigerating chamber, a can therein having 70 its bottom substantially upon the floor of said chamber, the can being provided with a nipple extending below the floor of the chamber, a second chamber below the floor of the refrigerating chamber, means for supplying refrigerant in the refrigerating chamber, means for supplying thawing medium to the second chamber, means for supplying water to said second chamber for filling the can, an air pipe and an air jet thereon with 80 in the second chamber and below and directed upwardly into said nipple.

3. In freezing tanks, the combination of a refrigerating chamber, a plurality of cans arranged in rows therein, a second chamber 85 below the floor of said refrigerating chamber, the cans being provided with nipples extending downward into said second chamber, air pipes lying below the bottoms of said nipples and provided with air jets below and directed upwardly into the nipples, means for supplying refrigerant to the refrigerating chamber, means for supplying water to be frozen to the second chamber, and means for supplying thawing medium 90 to the second chamber.

4. In freezing tanks, the combination of a refrigerating chamber, another chamber below the floor thereof, one or more cans in the refrigerating chamber, said cans communicating with said second chamber, means for supplying water to said second chamber and the cans, means for supplying thawing water to said second chamber, and means for maintaining a body of air at the top of said 100 second chamber during freezing and for removing the said body of air and causing the thaw water to directly contact with the bottom of the refrigerating chamber during thawing.

5. In freezing tanks, the combination of a freezing tank, one or more cans therein, each having a nipple extending below the floor of the tank, the chamber below the freezing tank inclosing said nipples, a closable air 115 vent communicating with said chamber substantially at the top thereof, means for supplying refrigerant to the freezing tank, means for supplying water to be frozen to said chamber, and means for supplying 120 thaw water to said chamber.

6. In freezing tanks, the combination of a freezing tank, cans therein resting substantially on the bottom of the tank, the cans being provided with nipples extending below said floor, a chamber beneath said freez-

ing tank and inclosing the nipples, an air pipe communicating with said chamber at approximately the top thereof, a closable vent in said pipe, an air gage communicating with said chamber near the top, means for supplying refrigerant to the freezing tank, means for supplying water to be frozen to said chamber, and means for supplying thaw water to said chamber.
